US0D1066101S

(12) **United States Design Patent** (10) Patent No.: **US D1,066,101 S**
(45) Date of Patent: ** Mar. 11, 2025

(54) **PENDANT**

(71) Applicant: **LOUIS VUITTON MALLETIER**,
Paris (FR)

(72) Inventors: **Laetitia Roze**, Paris (FR); **Francesca Amfitheatrof**, Paris (FR)

(73) Assignee: **Louis Vuitton Malletier**, Paris (FR)

(**) Term: **15 Years**

(21) Appl. No.: **29/891,458**

(22) Filed: **May 5, 2023**

Related U.S. Application Data

(62) Division of application No. 29/730,942, filed on Apr. 9, 2020, now Pat. No. Des. 1,016,654.

(30) **Foreign Application Priority Data**

Oct. 11, 2019 (FR) 2019-4462
